UNITED STATES PATENT OFFICE

MAX HERSKOVITZ, OF CHICAGO, ILLINOIS.

ATTACHMENT-PLUG.

1,162,921.

Specification of Letters Patent.

Patented Dec. 7, 1915.

Application filed November 16, 1914. Serial No. 872,313.

To all whom it may concern:

Be it known that I, MAX HERSKOVITZ, a citizen of the United States, and a resident of Chicago, Cook county, Illinois, have invented certain new and useful Improvements in Attachment-Plugs, of which the following is declared to be a full, clear, and exact description.

This invention relates to attachment plugs for use in making electric connections between plug sockets and flexible conductors, and its principal object is to provide an extremely cheap, simple and efficient plug, capable of use in connection with the standard form of socket.

The invention consists in the several novel features of construction, arrangement and combination of parts hereinafter set forth and claimed.

The invention is clearly illustrated in the drawing furnished herewith, in which:

Figure 1 is a side elevation of an attachment plug embodying a simple form of the present invention; Fig. 2 is a vertical cross section taken on line 2—2 of Fig. 1; Fig. 3 is a vertical cross section taken on line 3—3 of Fig. 2; Fig. 4 is a horizontal cross section taken on line 4—4 of Fig. 2; Fig. 5 is an end view looking in the direction of the arrow, 5, in Fig. 3; Fig. 6 is a perspective view of the side contact member detached from the body of the plug; and Fig. 7 is a perspective view of a clip forming part of the plug and serving to hold the end contact piece in place.

Referring to said drawing, the reference numeral, 10, designates the body of the plug, which is made of non-conducting material, as of china or porcelain, or the like, having a cylindrical portion, 11, for receiving the side contact member, 12, and provided at one end with a central opening, 13, for the admission of the flexible conducting members, and therebeyond formed with two conduits or passageways, 14, 15, one extending part way through the body and terminating in a laterally extending portion, 16, and the other extending from end to end of the body, 10. The short conduit leads to the side contact member, 12, and the long conduit leads to the end contact member, 17.

In the side of the cylindrical portion, 11, of the body, is formed a recessed portion, 18, for receiving a part, 12^a, of the side contact member, 12. Preferably, the

side contact member, 12, is constructed of light gage metal, and a metal block, 19, is inserted in the bottom of the depressed portion behind the part, 12^a, for receiving the binding screw, 20, which is threaded in registering holes formed in the part, 12^a, and block, 19. One of the wires of the conductor cord leads through the conduit, 14, and is secured to the side contact piece by 65 the binding screw, 20.

The side member, 12, consists of a ring-like piece of contact metal having the usual corrugated thread-like part, 12^b, which is adapted to be screwed into the standard 70 form of socket, and a smooth portion, 12^c, the end of which abuts against an annular shoulder, 21, formed on the body, 10. Movement of the side contact member in one direction relative to the body, is prevented by said shoulder, and movement in the other direction is prevented by the engagement of the inwardly bent part, 12^a, against the bottom of the recessed portion, and also by an inwardly dented portion, 22, 80 which enters a notch, 22^a, in the side of the body, opposite the recessed portion, 18. The end portion, 23, of the body is of less diameter than the part, 11, and is formed in its side with two diametrically opposite 85 notches, 24; the adjacent end of the side contact member, 12, projects under the shoulder formed between the part, 11, and reduced end, 23, and has two tongues or lugs, 25, which enter the notches, 24, and 90 prevent relative rotation between the body and side contact member.

The end contact member, 17, has a clip, 26, which is seated in a centrally disposed socket, 27, formed in one end of the body 95 and said clip has two arms, 28, which are bent back from the main portion of the clip so as to diverge from each other, and when inserted in said socket, 27, they engage with the lateral walls thereof with enough frictional contact to securely hold the clip in place in the socket. The outer contact piece, 29, of the end contact member is in the form of a washer having a depressed portion, 30, for receiving the head of a binding screw, 31, which is threaded in the main portion of the clip, 26. The second wire of the conducting cord is led through the long conduit, 15, and its end is wrapped around the shank of the binding 100 screw, 31, and secured in place by said screw, 31, and outer contact piece, 29.

The principal advantages of this attachment plug consist in its simplicity of construction, the ease with which the parts may be assembled and secured together, and the reduction of the parts to a minimum number.

More or less variation of the exact details of construction is possible without departing from the spirit of this invention, and I desire, therefore, not to limit myself to the exact form of construction shown and described, but intend in the following claims to point out all of the invention disclosed herein.

15 I claim as new and desire to secure by Letters Patent:

1. An attachment plug comprising a body portion having two conduits for the wires of a conductor cord and formed with a recessed portion in its side, and a ring-like, side contact member surrounding the said body portion and having a part thereof forced into said recessed portion of the body.

2. An attachment plug comprising a body portion having conduits for the wires of a conductor cord, notches in one end and a recessed portion in its side, an end contact member secured in the end of the body portion, and a cylindrical, side contact member having a threaded, corrugated part formed with inwardly projecting portions seated in said notches, and another inwardly depressed part seated in said recessed portion and there provided with a screw for attaching a wire of the conductor cord thereto.

3. In an attachment plug, a side contact member comprising a ring-like member having a corrugated portion formed with two inwardly extending lugs and a portion of its side being depressed toward its interior and there provided with a hole for the reception of a screw, and a thicker block of material adjacent said depressed portion for receiving the shank of the screw.

4. An attachment plug comprising a body portion having two conduits for the wires of a conductor cord, and a recessed portion in its side, one of said conduits terminating at said recessed portion and one extending from end to end of said body portion, a ring-like, metal, side contact member surrounding said body portion and having a corrugated, screw threaded portion and a part bent inwardly to lie in said recessed portion of the body portion, and prevent endwise movement of one member relative to the other, said inwardly bent part also

forming the terminal for one of the wires of 60 the conductor cord.

5. An attachment plug comprising a body portion having conduits for the wires of a conductor cord, a recessed portion in its side, and a notch in its side therebelow, and 65 a ring-like, side contact member surrounding said body portion and having a corrugated, screw threaded portion arranged to lie in said recessed portion of the body portion, and forming a terminal for one wire 70 of the conductor cord, said corrugated part having an inwardly projecting lug entering said notch in the body portion.

6. An attachment plug comprising a body portion having conduits for the wires of a 75 conductor cord, and reduced in diameter at one place to provide an annular shoulder, said reduced portion having a recess in its face opening to one of said conduits, and a ring-like, side contact member surrounding said reduced portion and abutting against said shoulder, said side contact member having a corrugated, screw threaded portion and a smooth portion formed with a depressed part lying in said 80 recess and forming a terminal for one of the wires of the conductor cord.

7. An attachment plug comprising a body portion having conduits for the wires of a conductor cord, one conduit extending 90 from end to end thereof, a centrally disposed socket in one end of said body portion, a metal clip sealed therein and having two diverging arms bearing against the side walls of said socket to hold the clip in place, 95 and an end contact piece having a screw threaded in said clip for securing one of the wires of the conductor cord thereto.

8. In an attachment plug having a centrally disposed socket in one end, a clip for 100 securing an end contact piece thereto, and comprising a metal body portion having diverging arms bent away therefrom and arranged to bear against the side walls of said socket, substantially as and for the purpose 105 specified.

9. In an attachment plug, a body portion having a centrally located socket in one end and a conduit opening thereto adapted for the reception of a conductor cord, and a 110 clip adapted for connection with a conductor cord lying in said conduit, said clip having arms projecting from its main portion into said socket and secured in said socket.

MAX HERSKOVITZ.
